UNITED STATES PATENT OFFICE.

CHARLES J. W. BRELAND, OF SPIRO, OKLAHOMA.

COMBINATION PENCIL SHARPENER AND HOLDER.

1,215,473.

Specification of Letters Patent. Patented Feb. 13, 1917.

Application filed February 11, 1915. Serial No. 7,535.

To all whom it may concern:

Be it known that I, CHARLES J. W. BRELAND, a citizen of the United States, residing at Spiro, in the county of Le Flore and 5 State of Oklahoma, have invented certain new and useful Improvements in Combination Pencil Sharpeners and Holders, of which the following is a specification.

My invention relates to a combination 10 holder and sharpener principally for use in connection with pencils.

The main object of the invention is to provide a neat, attractive, simple, effective and easily and cheaply manufactured construction of sharpener or knife blade and a holder, preferably in the form of a clasp holder by means of which an article such 15 as a pencil may be attached to the outer wall of a coat pocket.

Another object is to provide the article 20 of but two separately made elements, namely a holder and a blade, having co-operating details of construction to connect them in operative relation.

With the foregoing and additional objects 25 such as will hereinafter appear, the invention resides in the details of construction, arrangement and combination of parts as will be hereinafter described and claimed.

One preferred embodiment is illustrated 30 in the accompanying drawings wherein:—

Figure 1 is an elevation showing my improved article clasped to a pencil;

Fig. 2 is an elevation of my improved 35 article with the knife blade extended;

Fig. 3 is a longitudinal sectional view on line 3—3 of Fig. 2;

Fig. 4 is a fragmentary inverted plan view;

Fig. 5 is an end view and

Fig. 6 is an enlarged fragmentary sectional view taken on the line 6—6 of Fig. 2.

Referring specifically to the drawings a pencil holder is shown as having an elongated substantially, arcuate yieldable clasp portion 7 to receive a pencil 8 as seen in Fig. 1. The longitudinal edges of the clasp 7 are curved or rolled outwardly at 9 to facilitate pressure of the pencil 8 therebetween in connecting it with the holder. Also a yieldable clasp tongue 10 may extend from the clasp preferably slightly inwardly. The outer wall of a coat or vest pocket may be received and clasped intermediate tongue 10 and the pencil. It might be mentioned that all parts of the holder

are integral and that the holder is preferably made of bendable and yieldable spring metal or other material. This holder is to be considered as conventional.

In combination with the holder I employ a suitably shaped pencil sharpener which may be in the form of a knife blade 11 adapted to slide within and be concealed by the holder when connected to the pencil. (See Fig. 1.) Clasp 7 has a blade guide 12 integral therewith provided with laterally and inwardly extending bendable lugs 13 between and on which the blade 11 slides. Integral with the blade 11 is a transversely disposed stud 14 which extends through an elongated slot 15 provided in the clasp 7. Beyond the slot 15, stud 14 terminates in a finger piece or nib 16, wider than the slot, so as to overlap the clasp adjacent the sides 75 of the slot. Guide 12, slot 15 and stud 14 and nib 16 mount the blade 11 for sliding movement and against displacement from the holder.

When attached to a pencil, the clasp 7 receives the same and the blade 11 is retracted. Thus mounted, the holder may be clasped, as an ordinary clasp, to the outer wall of a coat or vest pocket by means of the tongue 10. Should it become necessary 85 or desirable to sharpen the pencil, the device is detached from the pencil and the holder grasped by one hand and the blade projected by sliding movement imparted by engagement of a finger of the other hand 90 with the nib 16. The end walls of slot 15 limit the movement of the stud and blade. The device may then be manipulated as an ordinary knife. After such use, the knife blade is retracted and the device again attached to the pencil. The frictional contact of the pencil against the knife blade and lugs 13 aided by the spring action of clasp 7 hold the blade against sliding movement.

Owing to the fact that the nib 16 is shorter than the width of the slot 15 the nib and stud 14 can be inserted in the slot 15 when the blade is held at a right angle to the holder. Lugs 13 at this stage being 105 straight, permit the blade to then be swung laterally midway of the lugs 13 whereupon these lugs are bent to the position shown in the drawings to complete the fastening of the blade and holder.

As merely the preferred embodiment has been illustrated and described it is to be

understood that changes in the details of construction may be resorted to within the spirit and scope of the invention.

I claim:—

- 5 1. In a sharpener device, in combination with a supporting article, a holder mounted on said article being inherently flexible to frictionally engage the article, a cutter blade disposed between the holder and article, said holder abutting the article and being tensioned to press the blade against the article, a head on said blade of a length corresponding to the width of the blade, a reduced stud extending at an angle to the 30 blade and integral with the blade and head, said holder having an elongated slot through which the head is passable when the cutter blade is disposed at an angle to the holder, the cutter blade being turnable 35 after passage of the head through the slot so that the head will overlap the holder at the slot, said holder at its active end having bendable lugs integral therewith, said bendable lugs being bent into overlapping engagement with the cutting blade at opposite longitudinal edges.
- 10 2. In a sharpener device, in combination with a supporting article, a holder mounted on said article being inherently flexible to frictionally engage the article, a cutter blade disposed between the holder and article, said holder abutting the article and being tensioned to press the blade against the article, said holder having an elongated slot, a stud integral with said blade at its inner end and of less width than the slot and passable through said slot and having a head to overlap the blade at the slot after turning of the blade subsequent to passage of the stud through the slot, and lugs on the holder to prevent lateral displacement 20 of the blade, said lugs being bendable and integral with the holder and at one end thereof overlapping the blade at opposite longitudinal edges, said lugs and stud extending in opposite directions laterally of 25 the blade.
- 15 2. In a sharpener device, in combination with a supporting article, a holder mounted

ed on said article being inherently flexible to frictionally engage the article, a cutter blade disposed between the holder and article, said holder abutting the article and being tensioned to press the blade against the article, a head on said blade of a length corresponding to the width of the blade, a reduced stud extending at an angle to the 30 blade and integral with the blade and head, said holder having an elongated slot through which the head is passable when the cutter blade is disposed at an angle to the holder, the cutter blade being turnable 35 after passage of the head through the slot so that the head will overlap the holder at the slot, said holder at its active end having bendable lugs integral therewith, said bendable lugs being bent into overlapping engagement with the cutting blade at opposite longitudinal edges.

In testimony whereof I affix my signature in presence of two witnesses.

CHARLES J. W. BRELAND.
